Filed May 2, 1960, Ser. No. 60,515

Term of patent 14 years

(Cl. D48—31)

FIG. 1

FIG. 2

FIG. 3

FIG. 4

FIG. 5

FIGURE 1 is a side elevational view of a street lighting lamp or the like, showing my new design;

FIGURE 2 is a top plan view thereof;

FIGURE 3 is a cross sectional view to a larger scale taken on line 3—3 of FIGURE 1;

FIGURE 4 is a cross sectional view to the same scale as FIGURE 3, taken on line 4—4 of FIGURE 1; and

FIGURE 5 is an enlarged fragmentary sectional view taken substantially along line 5—5 of FIGURE 2 to better illustrate the configurational details of the cylindrical band below the shade.

The tubes and inner elements are shown in broken lines in FIGS. 1, 3 and 5 for illustrative purposes only.

I claim:

The ornamental design for street lighting lamp or the like, substantially as shown and described.
